UNITED STATES PATENT OFFICE.

HARVEY L. BRYANT, OF BROOKLYN, NEW YORK, ASSIGNOR TO AMERICAN CAN COMPANY, OF SAN FRANCISCO, CALIFORNIA, A CORPORATION OF NEW JERSEY.

METHOD OF AND APPARATUS FOR COMPOUND LINING CAN ENDS.

Application filed February 24, 1920. Serial No. 360,624.

To all whom it may concern:

Be it known that I, HARVEY L. BRYANT, a citizen of the United States, residing at 156 4th Ave., Brooklyn, in the county of 5 Kings and State of New York, have invented certain new and useful Improvements in Methods of and Apparatus for Compound Lining Can Ends, of which the following is a specification.

10 The hereinafter described invention is more particularly designed for the compound lining of the flanges of what is commonly known as irregular-shaped can ends, the construction and operation of the inter- 15 connected working parts of the apparatus and the method of procedure being such that during the continuous travel of a can end from the receiving to the discharge end of the apparatus, the said end is turned 20 to expose the flange thereof to the means for applying the compound lining material thereon; the object of the invention being to facilitate the compound lining of the flange of irregular shaped can ends and to avoid 25 the transfer of the unlined can ends from the conveying means onto transfer means 30 for placing the said end within the sphere of the compound liner applying mechanism, thereby dispensing with the transfer of the 35 ends, and by so doing simplifying the construction and operation of the apparatus, producing more efficient means for the compound lining of the flange of the irregular shaped can ends, and materially increasing 40 the output of a compound lining apparatus.

The apparatus disclosed herein for carrying out the invention comprises means for conveying can ends continuously in a straight line as distinguished from machines of a circular or straight line intermittent type. In this invention the can ends are not retained during the period the lining material is being applied to their flanges. As far as I am aware all previous 45 machines for applying lining material to the flanges of can ends through the medium of valve controlled nozzles, rotate the can ends with the flange to be lined, describing a path directly under a fixed nozzle. In 50 order to do this the can ends must have intermittent movement through the machine, this necessarily restricts the output, because sufficient time must be allowed each period of rest to give the lining material 55 time to flow from the nozzle onto the flange

of the rotating can end. This kind of operation is particularly slow with the rectangular ends, for the lining of which this invention is particularly adapted. Practically all rectangular or irregular shaped can ends 60 have rounded corners, and while this is a straight line machine I have provided means through a slight swinging movement given to the lining nozzles, so the rounded corners are lined without in any manner 65 retarding the continuous forward movement of the can ends through the machine.

To comprehend the invention, reference should be had to the accompanying sheets 70 of drawings, wherein is illustrated a preferred embodiment of an apparatus for the practical carrying out of the invention, and wherein,

Fig. 1 is a plan view of the apparatus, 75 illustrating the path of travel of can ends therethrough, the said ends being shown as unlined, partly lined, and wholly lined.

Fig. 2 is a longitudinal sectional view taken on the line 2—2, Fig. 1 of the drawings, and viewed in the direction of the arrows.

Fig. 3 is a vertical sectional view, taken on line 3—3, Fig. 1, of the drawings, and viewed in the direction of the arrows, said view illustrating one of the can end or cover 85 carrier blocks with an end or cover held thereto positioned immediately in advance of the rolls for controlling and actuating the mechanism for supplying the compound lining material onto the flange of the can 90 end.

Fig. 4 is a similar view illustrating the cover carrier block intermediate the rolls for throwing the levers actuating the means controlling the supply of the compound 95 liner material; the valves controlling the outlet of the compound liner reservoirs being disclosed in raised position for the discharge of liner material onto the flange of a positioned can end or cover.

Fig. 5 is a broken longitudinal section plan view taken on the line 5—5 Fig. 4 of the drawings and viewed in the direction of the arrows, illustrating more particularly the construction of the frame of the apparatus, and the means for throwing the can end or cover carrier blocks after the side portion of the flange of the end has been compound lined.

Fig. 6 is a similar view illustrating one 110

of the can end or carrier blocks with its end or cover in partly turned position.

Fig. 7 is a detailed sectional view taken on line 7-7 of Fig. 2 of the drawings and viewed in the direction of the arrows, illustrating the means for restoring the can end or cover carrier blocks to normal position after the lined can end has been discharged therefrom.

10 Fig. 8 is an enlarged detail view illustrating one of the can end or cover carrier blocks and its connection with the endless conveyer.

15 In its preferred embodiment the operative apparatus for the carrying out of the invention comprises a suitable supporting frame, in the present case composed of angle members 1, 2, 3 and the transversely disposed connecting members 4. Longitudinally of 20 the frame and intermediate the side members 2 thereof, are disposed the spaced members 5, which are held a slight distance above the frame of the apparatus by means of the spacing blocks 5', Figs. 3 and 4 of 25 the drawings, and they are bolted or united to the end members 3 and the transversely disposed members 4 by means of suitable bolts 5^a (Fig. 1) passing through the spacing blocks. Intermediate of the members 5 30 is located a longitudinally disposed channeled member 6, which provides a longitudinal guide-way 6' in which travels the upper run of an endless travelling conveyer or carrier 7, which, in the present case, is illustrated as comprising an endless chain.

35 The endless carrier 7 is provided with a series of upwardly projecting spaced lugs or flights 8, to which are secured the can end or cover supports, carriers or carrier blocks 9. The circular head extension 8' of each lug or flight 8 projects through a central aperture in the carrier blocks 9, each block being rotatably held to its flight 8 by means of a securing screw 10, which holds a 40 washer 11 within a central counter-sunk portion in the upper face of the said cover block 9, Fig. 4 of the drawings. Each carrier block 9 is free to rotate or turn on the circular extension of the lugs of the endless carrier when the said blocks are acted on by 45 the means for shifting or turning the position thereof as the blocks are carried successively past the compound liner stations of the apparatus hereinafter referred to. 50 The endless carrier 7 works over the end sprockets 11 and 12 of the apparatus, Fig. 2 of the drawings, the sprocket 12 being driven by any suitable outside source of the power applied to the belt pulley 13, which 55 pulley is mounted on the shaft 14 to which the sprocket 12 is attached; the shaft 14 and 60 equally so, the shaft 14' for the sprocket 11, working in suitable bearings of the apparatus. To maintain the tension of the endless 65 carrier 7 or prevent loose play thereof, there

is provided an idler sprocket 15 which engages with the underrun of the said endless carrier, Fig. 2 of the drawings, the said idler sprocket 15 being secured to or carried at the inner or free end of a downwardly extended 70 arm 16, pivoted at its upper end portion to the frame structure of the apparatus.

At any suitable point relative to the apparatus is provided a can end or cover holding table 17, Figs. 1 and 2 of the drawings, 75 from which leads a downwardly inclined feed chute 18, which at its lower end has attached thereto an outwardly projecting spring-clip 19; the said clip being attached to a centrally disposed retaining bar 20 located within the sphere of the feed chute 18, and which retaining bar prevents the can covers or ends 21 from becoming displaced as the same move by gravity down the inclined feed chute 18.

80 Each carrier block 9 is of a shape corresponding to the panel of the can cover or end 21 the flange of which is to be compound lined, being herein shown as rectangular with rounded corners, which shape is to be varied to correspond with the shapes of can ends of other contour which are to be lined with compound, and the covers 21 as they leave the chute 18 rest at their forward end onto the two supporting blocks 22, secured to the upper face of the longitudinal plates 23, which plates in turn are attached to the upper portion of the channeled guide member 6 for the endless carrier. Two pairs of guides are utilized in the present apparatus, the first pair 23 terminating at a point just beyond the first pulp lining station A of the apparatus, while the second pair of guides 23' extend from a point just beyond the trip mechanism for the carrier blocks and terminate at a point beyond the second compound lining station B, Figs. 1, 5 and 6 of the drawings. The carrier blocks are held a slight distance above the guides 23 and 23' and each block below its upper portion for engaging with the panel of the can ends or covers is provided with a cam surface 24, shaped to the contour or configuration of the can end or cover 21, the flange of which is to be lined, and below the cam surface portion 24 thereof is formed with a square portion 25, Fig. 8 of the drawings. The square portion 25 of the carrier blocks contacts with the inner walls of the guides 23 and 23' during the course of travel of the carrier blocks through the apparatus and by means of these guides the said blocks are held against turning movement, so long as the said blocks are within the sphere of the said guides.

120 In the present apparatus two pulp lining stations are provided, viz: station A and station B. At each of the lining stations above the frame of the apparatus is mounted a plurality of holding reservoirs for the com- 125

ound liner material, which reservoirs are arranged in pairs at each station, being designated respectively by the numerals 25 and 25² and 26 and 26'. Each compound holding reservoir is secured to a laterally movable U-shaped bracket 27, mounted or secured to the swinging arms 28, which said arms are pivotally secured to the longitudinal members 5, Figs. 3, 4 and 5 of the drawings. There is interposed between the brackets 27 and the pivotal arms 28, the spacer blocks 28' said blocks at their inner ends being downwardly and inwardly bent so that the free ends thereof lie in a plane slightly below the member 5, and to the free ends of each block is mounted a roller 29, which rollers work over the cam surface 24 of the carrier blocks 9. It will be understood that these rollers would work similarly on carrier blocks of other shape, corresponding with other can ends to be treated. Each pair of pivotal arms 28 are held inwardly pressed at their free ends by the tension of the connecting springs 30, Figs. 1, 3 and 4 of the drawings, in which inwardly pressed position they are maintained until spread apart by the pressure of a travelling carrier block onto the follower rolls 29, as the said blocks with a cover applied thereto are carried past either of the compound lining stations.

Each compound holding reservoir is provided with a valve-controlled outlet 31, the escape of compound through the outlet 31 of each reservoir being controlled by a needle valve 32, the stem 32' of which valve extends beyond its holding reservoir and is formed slightly larger than the needle valve, and at its lower end is screw-threaded to receive a collar 33 against which a spring 33' bears, said spring surrounding the stem of the needle valve and being confined between the collar 33 and the inner end of a bracket 34 upwardly projecting from the reservoir 25'. The compound lining material is supplied under pressure to the compound holding reservoirs 25', 25², 26 and 26', by means of the feed tubes 35, which tubes lead from any suitable source of pressure supply, Figs. 2, 3 and 4 of the drawings.

As the rollers 29 work over the cam surface of the carrier blocks 9 during the movement of the endless carrier through the apparatus, the U-shaped brackets 27 supporting and carrying the compound holding reservoirs 25 are caused to move inwardly and outwardly with the travel of the said rollers over the cam surface 24 of the carrier blocks 9, and as moved the lower arm *a* of a crank lever 36 engages with a horizontally disposed spring-held rod 37, Figs. 3 and 4 of the drawings so as to throw the upper arm *b* of said lever to raise the needle valves 32 to open the discharge outlet 31 of the reservoirs and permit the escape of liner com-

pound from within the said holding reservoirs. The moment a carrier block with a can end or cover supported thereon is by the travel of the endless chain or carrier moved from within the sphere of the said rolls 29, the action of the springs 30 draws inwardly the free ends of the swinging arms 28 and carrying therewith the U-shaped brackets 27 places the lower arm *a* of the crank levers 36 out of engagement with the spring-held rods 37, when the tension of the spring 33' gradually lowers the needle valves 32 to close the outlets 31 of the liner material holding reservoirs to cut off the escape of the material therefrom.

The outward movement of the rolls 29 riding over the cam surfaces of the carrier blocks 9 is so timed that the movement begins just as the can end is approaching the nozzles 31. This preliminary outswing of the reservoirs 25' and 25² and the nozzles 31 causes them to describe a curved path approximately in shape to that of the rounded corners of the approaching rectangular can ends. This action operates means that starts the flow of compound just as the outlets of the nozzles 31 are directly over the rounded corner flanges, so that the initial application of compound is on the curves of the flanges, passing immediately onto the straight side. The reverse action takes place just as the can ends pass away from the nozzles 31. The rolls 29 riding inward over the cam surfaces of the blocks 9 cause the nozzles 31 to describe a path similar to the curved corners of the passing can ends and apply compound thereto during this final swinging movement. It is not necessary to apply the compound over the entire curve at the first station, since the action at the second lining station is similar. It is therefore only necessary to have the parts and movements so timed that the lining material applied at the corners overlaps, on account of its fluid nature it will run together and make a continuous film with the lining material applied on the straight sides of the flanges. Fig. 3 of the drawings shows the reservoirs 25 and 25² in their normal inoperative position with the nozzles 31 lying within the path of the straight portion of the can flanges and in the position at which they begin to move outward and discharge lining material around the approaching curved corners of a can end.

During the movement of the carrier blocks 9 through the apparatus with ends or covers applied thereto for lining, the can ends or covers are held to the carrier blocks and prevented against upward movement or displacement by means of the longitudinally disposed guard rail 38 which is arranged centrally of the apparatus above the said blocks and held a slight distance above the upper surface of the covers applied thereto.

As the lined can ends or covers 21' approach the discharge end of the machine, the same are delivered onto the spaced angle stripper bars 39, which serve as the discharge portion of the apparatus for the lined can ends or covers, the said ends or covers being delivered onto the forward end of the said bars as the carrier blocks approach for travel over the sprocket 12; the carrier blocks at such time passing between stripper bars 39 and the can end or cover being stripped, so to speak, from the said blocks, it being understood that each succeeding can end or cover as delivered onto the stripper bars gradually pushes the previously deposited lined ones thereover. The lined can ends as forced along or over the stripper bars 39 are held in place by the retaining rail or plate 39', which, if so desired, may constitute a continuation of the retaining plate or rail 38.

Just beyond the pair of spaced follower rolls 29 which are situated at the liner station A, is located a horizontally disposed trip dog 40, which is pivotally connected for swinging movement to the upper face of one of the guide plates 23, Figs. 1, 5 and 6 of the drawings. This trip dog is normally held inwardly pressed by a spring 40', so as to cause the hooked end 41 thereof to project within the path of travel of the square portion 25 of the carrier blocks 9 of the endless carrier 7. With the dog thus positioned, as a carrier block is moved beyond the lining station A, the hooked end thereof engages the square portion of the carrier blocks and by reason of the pulling strain exerted thereon by the travel of the endless carrier, the carrier block with a can end or cover thereon is turned or part rotated to place its unlined end flange wall portion *e* for alignment with the discharge outlets of the compound holding reservoirs 26 and 26' situated at the lining station B of the apparatus, the end flange wall portion *d* of the can end having received liner material from the reservoirs 25' and 25'', as advanced beneath the same with the flange walls *d* positioned parallel with the central guide way of the apparatus.

In the compound lining of the flange of can ends or covers, the operation of the described apparatus is as follows:—

The can ends 21 delivered from the table 55 17 move down the inclined chute 18 until the same project below the lower end thereof, at which time the can end rests on the blocks 22 and stands at an inclination to the horizontal, being held in position by 60 the spring-clip 19. The can end at such time overlies the guide-way formed by the channeled guide member 6, the side flange portion *d* of the unlined can end being parallel with the discharge outlets of the liner compound holding reservoir 25' and

25'' and the forward edge of the panel of the can end being in a plane slightly below that of the upper surface of a can carrier block of the endless carrier. As a carrier block 9 of the endless carrier is advanced, 70 the forward edge thereof engages with the inner surface of the panel of the positioned can end and draws the same from off the chute 18 and supporting blocks 22, the can end gradually lowering onto the can end carrier block. The can end thus positioned is advanced by the continued movement of the endless carrier toward the lining station A, where as the carrier block moves between the follower rolls 29, the said rolls and the pivoted arms 28, together with the connected brackets 27 are moved outwardly or spread apart, the movement of these members corresponding with that of the follower rolls 29, working over the cam portion 24 of the rotatable carrier blocks. As the members actuated by the movement of the first pair of follower rolls 29 over the cam portion 24 of the carrier block 9 during the advancing movement thereof between the said rolls are moved, the compound holding reservoirs move therewith to place the discharge outlets thereof in axial alignment with the portion *d* of the flange of the can end to be lined, at the same time the throw 95 imparted to the crank levers 36 raising or unseating the valves 32 of the reservoirs to permit the escape of the liner compound therefrom and the flow thereof onto the unlined portion *d* of the flange of the can end. 100

The spring-held follower rolls 29 gradually move inwardly for throwing the crank levers 36 to close the discharge outlet of the liner material holding reservoirs as the carrier block 9 with its applied can end moves from within the sphere of the said rolls. The partly lined can end is then advanced toward the lining station B, and during such movement the pivotal spring-held dog 40 engaging with the square portion 25 of 110 the carrier block 9 and the pulling strain exerted thereon causes the gradual turning or part rotation of the carrier block 9 until the unlined portion *e* of the flange of the can end is placed in position for axial alignment with the discharge outlet of the holding reservoirs 26 and 26'. As the turned carrier block, after moving from within the sphere of the trip dog 40 advances between the second pair of follower rolls 29 situated 120 at the second lining station B, the said spring-held follower rolls 29 are forced apart or outwardly, riding at such time over the cam portion 24 of the carrier block 9. This movement of the said follower rolls 125 outwardly moves the swinging arms 28 and the U-shaped brackets 27, to place the discharge outlets of the reservoirs 26 and 26' in axial alignment with the unlined portion *e* of the can end flange. As thus moved out- 130

wardly, the spring-held rods 37 engage with and force inwardly the lower arm *a* of the pivotal crank levers 36, causing an upward throw of the arm *b* of said levers to raise or unseat the valves 32 of the liner compound holding reservoirs 26 and 26' to permit an escape of the compound therefrom and the flowing thereof onto the unlined portion of the can end flange during the longitudinal 10 advance through the machine of the carrier block 9 on which the can end is supported. On the carrier block with its supported can end moving from within the sphere of the follower rolls 29, a reverse movement is imparted to the described parts which are restored to normal position. It will be understood that the action of the second pair of follower rolls and their associated parts situated at the lining station B is the same 20 as the action of the corresponding parts situated at the lining station A.

As an end carrier block with a flanged lined can end thereon approaches the sprocket 12 at the discharge end of the apparatus, the under surface of end portions of the can end flange projecting beyond the side wall surface of the carrier block is engaged by the inner end of the spaced stripper bars 39 and gradually lifted from the carrier block as the said block is carried over the sprocket 12 by the travel of the endless carrier. At this time the carrier block is so positioned that its longitudinal axis stands transverse or at right angles to the longitudinal axis of the guide-way of the apparatus; consequently, it is required that the same may be turned or part rotated to its normal position, that is with its longitudinal axis in parallelism with the longitudinal axis of the guideway 6' within which works the endless conveyer or carrier 7. This turning places or positions the carrier blocks discharged of lined can ends in position to receive an unlined can end as they move beneath the spring clip 19 at the lower end of the feed chute 18 for the can ends. In order to accomplish this turning or part rotation of the can end carrier blocks as moved over the sprocket 12, there is secured to one of the stripper bars 39 a depending bracket 41', Figs. 1, 2 and 7 of the drawings, to the lower end of which bracket is pivoted for transverse swinging movement a vertically disposed trip dog 42, the hooked end 55 43 of which is normally held inwardly pressed by a spring 43' to lie within the path of travel of the carrier blocks and to engage with the square portions 23 thereof as the same move from beyond the sprocket 12. 60 This trip dog 42 acts in the same manner as the trip dog 40 which imparts initial rotation to the carrier blocks and serves to restore the blocks to the position held prior to being acted on by the said trip dog 40. 65 While I have described the preferred em-

bodiment of the invention as embodied in an apparatus in practical operation at the present time, it will be understood that I do not limit or confine myself to the detail construction of the described inter-connected working instrumentalities, being aware that the working parts described may be varied and changed without causing a departure from the invention, and therefore, I wish to be understood as claiming the invention as broadly as the state of the art may warrant. 70

Having thus described my invention what I claim as new and desire to protect by Letters Patent is:

1. An apparatus for the described purpose, the same comprising a series of rotat- 80 ing carriers for receiving unlined flanged can ends and advancing the same throughout the apparatus, a plurality of spaced lining stations past which the ends are moved, 85 mechanism situated at each of said stations for applying lining compound to the flange of a can end, and means interposed between said stations for imparting a part rotation to the said carriers and can ends to position the unlined portions of the flange of the ends to receive thereon lining compound at the second lining station of the apparatus. 90

2. An apparatus for the described pur- 95 pose, the same comprising an endless car- rier for receiving and transporting can ends through the apparatus, spaced rotatable can end supports secured to the said carrier for receiving irregular shaped can ends, a plu- 100 rality of lining stations situated within the path of travel of the carrier, valved controlled compound liner applying mechanism situated at each of said stations, means actuated by the advancing movement of the rotatable can end supports for actuating the compound applying mechanism, and means interposed between the lining stations for part rotating the can end supports after passing the first lining station for position- 105 ing unlined portions of a can end flange to receive lining compound at the second lining station. 110

3. An apparatus for the described pur- 115 pose, the same comprising a carrier for con-veying flanged can ends through the ap- 120 paratus, rotatable can end supports secured in spaced relation to the said carrier, sepa- 125 rated compound liner applying mechanism situated within the path of travel of the rotatable can end supports, means acted on by the advancing movement of the can end supports for actuating the liner applying mechanism for delivering liner compound to unlined portions of the can end flange, and means for imparting a part rotation to the can end supports intermediate the liner ap- 130 plying mechanisms.

4. An apparatus for the described pur- 130 pose, the same comprising a plurality of spaced liner stations, mechanism situated at

- each station for applying lining compound to the flange of can ends, a series of individually rotatable can end carriers for advancing can ends successively to said stations, and means interposed between said stations for imparting a part rotation to the said carriers as moved from the first liner station to the second liner station.
5. In an apparatus for the described purpose, the combination with an endless travelling carrier, a plurality of spaced rotatable can end supports united thereto for receiving can ends to be lined, a plurality of lining stations situated within the path 10 of travel of the said carrier, valve controlled liner compound reservoirs situated at each lining station in a plane above the plane of the travelling carrier, means acted on at each station by the can end supports for 15 actuating the mechanism for controlling the valve outlets of the reservoirs, and means interposed between the liner stations and within the path of travel of the can end supports for imparting thereto a part rotation as advanced from one liner station to the other.
6. In an apparatus for the described purpose, the combination with a continuous 20 lineal travelling carrier, spaced rotatable can end supports united thereto, spaced liner applying mechanisms within the path of travel of said carrier, means for actuating the lining applying mechanism associated with each liner applying mechanism acted 25 on by the can end supports during the movement thereof through the apparatus, and means interposed between said liner applying mechanisms for imparting part rotation to the can end supports as moved from one 30 of said mechanisms to the other.
7. An apparatus for the described purpose, the same comprising a plurality of 35 separated lining stations, of interconnected working instrumentalities situated at each lining station for delivering lining compound to the flange of can ends, individually rotatable can end carriers for receiving and advancing irregular shaped flanged can ends successively to said lining stations, and devices for imparting part rotation to 40 said carriers as advanced from the first lining station to the second lining station of the apparatus.
8. In an apparatus for the described purpose, the combination with an endless travelling carrier, of spaced can end supports rotatably held thereto, a plurality of spaced lining stations, and means interposed between said stations for imparting a part 45 rotation to the can end supports as advanced from the first to the second lining station.
9. In an apparatus for the described purpose, the combination with an endless carrier, of spaced can end supports rotatably 50 held thereto, a plurality of spaced lining stations, and a spring held trip situated within the path of travel of the can end supports and intermediate the lining stations, said trip acting to impart rotation 55 to the can end supports as advanced from the first to the second lining station.
10. In an apparatus for the described purpose, the combination with an endless carrier, of spaced can end supports rotatably held thereto, a plurality of spaced lining stations, a spring held trip situated within the path of travel of the can end supports and intermediate the lining stations, said trip acting to impart part rotation 60 to the can end supports as advanced from the first to the second lining station, and means for restoring the can end supports to normal position as advanced from the discharge toward the feed end of the apparatus.
11. In an apparatus for the described purpose, the combination with an endless carrier, of a plurality of spaced can end supports rotatably united thereto, a plurality of spaced lining stations, a pair of spaced valved controlled compound liner material holding reservoirs situated at each lining station above the said carrier, means 65 acted on by the can end supports for placing the discharge outlet of the reservoirs in actual alignment with the flange of can ends held to said supports and for actuating the valve thereof for the discharge of liner material therefrom, and means interposed between the lining station for imparting a part rotation to the can end supports as moved beyond the first lining station for 70 positioning unlined portions of the flange of can ends to receive lining material as 75 moved toward the second lining station.
12. An apparatus for the described purpose, the same comprising a plurality of spaced lining stations, an endless carrier for carrying flanged can ends past each of said 80 stations without transfer, a plurality of spaced can end supports rotatably held to said carrier, mechanism at each lining station for applying a lining compound to the flange of can ends as moved thereby, devices 85 acted on by the can end supports for actuating said mechanism, and means interposed between the lining stations for imparting part rotation to the can end supports as advanced from the first to the second lining station.
13. In an apparatus for the described purpose, the same comprising an endless carrier for conveying can ends through the apparatus, a plurality of spaced can end supports rotatably held to said carrier, valve-controlled mechanism at two stations 90 for applying lining material to the flange of the can ends during the movement of the carrier, means for giving a definite 95

part rotation to said supports in the interval between said stations, and means acted on by the can end supports for actuating said liner applying mechanism.

- 5 14. An apparatus for the described purpose, the same comprising an endless carrier for conveying flanged can ends through the apparatus without transference, a plurality of separated can end supports rotatably united to said carrier, a pair of spaced laterally movable valved controlled liner material holding reservoirs situated at each of said lining stations, means acted on by the can end supports as moved past said 70
- 10 15 station for actuating said reservoirs and the valves thereof for controlling the discharge of liner material therefrom onto the flange of the can ends, a trip device interposed between the lining stations for part 75
- 20 20 rotating the can end supports for positioning unlined positions of the flange of can ends to receive liner material at the second lining station, and means for restoring the can end supports to normal position as 80
- 25 25 moved from the discharge to the feed end of the apparatus.

15. An apparatus for the described purpose, the same comprising an endless carrier, a plurality of rotatable can end supports secured thereto in spaced relation and each being provided with a cam section shaped to conform to the contour of the can end to be lined, valve-controlled compound liner applying mechanism situated 85
- 30 35 within the path of the travel of the endless carrier, and means adapted to be acted on by the cam section of the can end supports for actuating the said valve-controlled liner applying mechanism during the movement 90
- 40 45 of the endless carrier.

16. An apparatus for the described purpose, the same comprising an endless carrier for advancing can ends through the apparatus, a plurality of rotatable can end supports secured thereto in spaced relation and each being provided with a cam section to conform to the contour of the can end to be lined, a plurality of spaced lining stations situated within the path of travel 95
- 50 55 of the endless carrier, valved controlled compound liner applying mechanism located at each lining station, means adapted to be acted on by the cam section of the can end supports for actuating the said valve controlled liner applying mechanism during the movement 100
- 60 65 of the said supports, and means interposed between the lining stations for imparting part rotation to the can end supports as advanced from the first toward the second lining station.

17. An apparatus for the described purpose, the same comprising an endless carrier, a plurality of rotatable can end supports united thereto in spaced relation and each provided with a cam section shaped 105

to conform to the contour of the can end to be compound lined, compound liner applying mechanism, and means acted on by the cam section of the can end supports for actuating said mechanism during the movement of the endless carrier. 70

18. An apparatus for the described purpose, the same comprising an endless carrier, a plurality of rotatable can end supports united thereto in spaced relation and each provided with a cam section shaped to conform to the contour of an end to be lined, a plurality of spaced lining stations, compound liner applying mechanism situated at each of said stations, devices acted 80

on by the cam section of the can end supports for successively actuating said mechanisms during the movement of the endless carrier, and means interposed between the 85

lining stations for imparting part rotation to the can end supports as advanced from the first toward the second lining station.

19. An apparatus for applying lining material to the flanges of round cornered rectangular or irregular shaped can ends, to act as a yielding sealing medium when said can ends are united to flanged can bodies by interfolded joints or seams, comprising means for moving can ends continuously in a straight line, means for holding said can ends from lateral displacement, a plurality of liner material applying stations, liner applying nozzles at said stations, means for imparting a movement to the said nozzles at each of said stations whereby lining material is applied to the rounded corners and to other portions of the flanges of each can end while passing the said stations. 95

20. An apparatus for applying lining material to the flanges of round cornered or rectangular can ends to act as a yielding sealing medium when said can ends are united to flanged can bodies by interfolded joints or seams, comprising means for controllably moving can ends in a straight line 100

110 past liner material applying stations, liner applying nozzles at each of said stations, said nozzles having discharge openings occupying a vertical position over the said flanges of said can ends, means for moving said nozzles in paths conforming to the rounded corners of said can ends, and holding said nozzles against movement during the lining of the straight portions of said can ends, means at each station for releasing lining material from said nozzles to be applied to the passing flanges of said can ends. 115

21. An apparatus for applying liner material to the flanges of irregular shaped can ends to act as a yielding sealing medium 120

125 when said can ends are united to flanged can bodies by interfolded joints or seams, comprising means for moving can ends to and past liner material applying stations, liner applying means at said stations, said liner 130

applying means being located over the flanges of said can ends, means for moving said liner applying means in a path conforming in shape to the flange of an irregular shaped can end while the liner material is being applied thereto.

22. An apparatus for applying liner material to the flanges of irregular shaped can ends to act as a yielding sealing medium when said can ends are united to flanged can bodies by interfolded joints or seams, comprising means for moving can ends continuously along a fixed path to and past liner material applying stations, vertically disposed means at said stations comprising openings for discharging liner material upon the flanges of can ends while moving past said stations and means for moving and holding the liner material discharge openings in operative relation with said can end flanges during the liner material applying period.

23. An apparatus for applying liner material to the flanges of irregular shaped can ends to act as a yielding sealing medium when said can ends are united to flanged can bodies by interfolded joints or seams, comprising a plurality of pairs of liner applying devices arranged at stations along the line of travel of a succession of flanged irregular shaped can ends, vertically disposed means associated with each lining device for delivering a determined quantity of liner material and for moving said liner applying devices to conform to the outline of the can end flange and apply two distinct separated portions of liner material onto the flange of the moving can end.

24. An apparatus for applying liner material to the flanges of irregular shaped can ends to act as a yielding sealing medium when said can ends are united to flanged can bodies by interfolded joints or seams, comprising a plurality of pairs of vertically disposed liner applying devices arranged along the line of travel of a succession of flanged irregular shaped can ends, means associated with one pair of said liner applying devices for delivering a determined quantity of liner material, comprising liner material discharge nozzles, means for actuating said nozzles to discharge liner material and means for moving said nozzles to conform to the outline of the can end flange while moving past same, to apply two distinct and separated portions of liner material onto the flange of each can end as it passes, and means associated with another pair of liner applying devices for applying two distinct and separated portions of liner material on the same said can end flange and connecting with the two said first applied portions to complete the lining of said can end.

25. An apparatus for applying liner material to the flanges of irregular shaped can

ends to act as a yielding sealing medium when said can ends are united to flanged can bodies by interfolded joints or seams, comprising a plurality of vertically disposed liner material applying devices arranged along the line of travel of a succession of flanged irregular shaped can ends, each liner applying device having associated therewith a discharge nozzle for delivering liner material to a predetermined portion of the flange of each can end as it passes, means for releasing a portion of liner material from each of said nozzles as a can end passes, and means for moving said nozzles to conform to the outline of the flange of each can end as it passes, each of said nozzles depositing its portion of liner material on a different section of the flange of each can end, whereby the combined liner material from all of the nozzles forms a complete and endless lining on said flange of each can end.

26. An apparatus for applying liner material to the flanges of can ends to act as a yielding sealing medium when said can ends are united to flanged can bodies by interfolded joints or seams, comprising a series of liner applying devices arranged along the line of travel of a succession of flanged can ends, each liner applying device having associated therewith a vertically disposed discharge nozzle for delivering liner material to a predetermined portion of the flange of each can end as it passes, means for releasing a portion of liner material from each nozzle, means for moving said nozzles to conform to the outline of the flange of each can end, each of said nozzles depositing its portion of liner material on a different section of the flange of each can end, giving each can end a partial rotation during its travel, whereby the combined liner material from all of the nozzles forms a complete lining on each flange of each can end.

27. A method of applying liner material to the flanges of can ends to act as a yielding sealing medium when said can ends are united to flanged can bodies by interfolded joints or seams, comprising moving can ends in succession past a series of vertically disposed liner applying devices, causing each liner applying device to deposit a portion of liner material on a different section of the flange of each can end as it passes, whereby the combined portions of liner material deposited by each liner applying device forms a complete lining covering the whole flange of each can end.

28. A method of applying liner material to the flanges of can ends to act as a yielding sealing medium when said can ends are united to flanged can bodies by interfolded joints or seams, comprising the moving of can ends into operative relation with one after the other of a series of vertically dis-

posed liner applying devices, causing each liner applying device to deposit a portion of liner material on a section of the flange of a can end, whereby all of the separate portions of liner material will form a complete lining for the said flanges of each of the said can ends.

29. A method of applying liner material to the flanges of can ends to act as a yielding sealing medium when said can ends are united to flanged can bodies by interfolded joints or seams, comprising the moving of can ends into operative relation with a series of vertically disposed liner applying devices, causing each liner applying device to deposit a portion of liner material on a section of the flange of a can end, giving each can end a partial rotation during its travel past said liner applying devices, whereby all sections of the flange will receive a portion of lining material.

30. A method of applying liner material to the flanges of can ends to act as a yielding sealing medium when said can ends are united to flanged can bodies by interfolded joints or seams, comprising moving can ends in succession to and past liner applying devices, causing each liner applying device to simultaneously deposit a portion of a fluid or semi-fluid liner material on different sections of the flange of a can end.

31. A method of applying liner material to the flanges of can ends to act as a yielding sealing medium when said can ends are united to flanged can bodies by interfolded joints or seams, comprising moving can ends in succession to and past liner applying devices, causing each liner applying device to simultaneously deposit portions of a fluid or semi-fluid liner material on opposite sections of the flange of the can end, whereby the combined portions of lining material from all of the devices form a complete lining for the flanges of the can ends.

32. A method of applying liner material to the flanges of can ends to act as a yielding sealing medium when said can ends are united to flanged can bodies by interfolded joints or seams, comprising moving can ends in succession to and past pairs of liner applying devices, causing each pair of liner applying devices to deposit simultaneously, portions of a fluid or semi-fluid liner material on different sections of said flanges, whereby the combined portions of applied lining material from all of the devices form a complete lining for the flange of the can end.

33. A method of applying liner material to the flanges of can ends of irregular contour to act as a yielding sealing medium when said can ends are united to flanged can bodies by interfolded joints or seams, comprising moving can ends to and past liner

applying devices, causing each liner applying device to follow the contour of the flange of each can end as it moves past said liner applying device and deposit a portion of a fluid or semi-fluid liner material on that section of the flange of said can end moving in operative relation therewith.

34. A method of applying liner material to the flanges of can ends of irregular contour to act as a yielding sealing medium when said can ends are united to flanged can bodies by interfolded joints or seams, comprising moving can ends to and past liner applying devices, causing each liner applying device to follow the contour of the flange of each can end as it moves past said liner applying device and deposit a portion of a fluid or semi-fluid liner material on that section of the flange of said can end moving in operative relation therewith and causing each can end to make a partial rotation before the application of the last portion of liner material thereto, whereby all sections of the can end flange receive a portion of lining material.

35. An apparatus for applying liner material to the flanges of can ends to act as a yielding sealing medium when said can ends are united to flanged can bodies by interfolded joints or seams, comprising, liner applying devices, means moving can ends in succession to and past said liner applying devices, and means causing each liner applying device to simultaneously deposit a portion of a fluid or semi-fluid liner material on different sections of the flange of a can end.

36. An apparatus for applying liner material to the flanges of can ends to act as a yielding sealing medium when said can ends are united to flanged can bodies by interfolded joints or seams, comprising, liner applying devices, means moving the can ends in succession to and past said liner applying devices, and means causing each liner applying device to simultaneously deposit portions of fluid or semi-fluid liner material on opposite sections of the flanges of the can ends whereby the combined portions of the lining material from all of the devices form a complete lining for the flanges of the can ends.

37. An apparatus for applying liner material to the flanges of can ends to act as a yielding sealing medium when said can ends are united to the flanged can bodies by interfolded joints or seams, comprising, liner applying devices, means moving the can ends to and past a pair of said liner applying devices, means causing each pair of liner applying devices to deposit simultaneously portions of a fluid or semi-fluid liner material on different sections of said flanges whereby the combined portions of the applied lin-

ing material from all of the devices form a complete lining for the flange of the can end.

38. An apparatus for applying liner material to the flanges of can ends of irregular contour to act as a yielding sealing member when said can ends are united to the flanged can bodies by interfolded joints or seams, comprising, liner applying devices, means moving can ends to and past said liner applying devices, means causing each liner applying device to follow the contour of the flange of each can end as it moves past said liner applying device and deposit a portion of a fluid or semi-fluid liner material on that section of the flange of said can end moving in operative relation therewith.

39. An apparatus for applying liner material to the flanges of can ends to act as a yielding sealing medium when said can ends are united to flanged can bodies by interfolded joints or seams, comprising, two pairs of liner applying devices, the members

of each pair being spaced apart, and means moving the can ends to present first two opposite sides to a pair of said liner applying devices and then the remaining parallel sides to the second pair of liner applying devices.

40. An apparatus for applying liner material to the flanges of can ends to act as a yielding sealing medium when said can ends are united to flanged can bodies by interfolded joints or seams, comprising, conveying means for a can end of substantially rectangular shape, liner applying devices arranged along the side of said conveying means and adapted to line opposite, substantially parallel flanges thereof, said conveying means presenting first one pair of opposite flanges to said liner applying devices and then the other pair of opposite parallel flanges.

In testimony whereof I have signed my name to this specification.

HARVEY BRYANT.
